Primary Examiner — Kevin K Rudzinski*Assistant Examiner* — Jeremy S. Swartz(74) Attorney, Agent, or Firm — Workman Nydegger(57) CLAIM

The ornamental design for a bed, as shown and described.

DESCRIPTION

FIG. 1 is a front perspective view of a bed showing the new design;

FIG. 2 is a front elevation view thereof;

FIG. 3 is a back elevation view thereof;

FIG. 4 is a top plan view thereof;

FIG. 5 is a bottom plan view thereof;

FIG. 6 is a right elevation view thereof; and,

FIG. 7 is a left elevation view thereof.

The broken lines shown in the figures illustrate portions of the bed that form no part of the claimed design.

1 Claim, 4 Drawing Sheets(56)
